Patented Mar. 19, 1963

194,856

INTELLIGENCE TRANSMITTER AND RECEIVER

Eliot F. Noyes, New Canaan, Conn., assignor to International Business Machines Corporation, New York, N.Y., a corporation of New York

Filed June 16, 1961, Ser. No. 65,615

Term of patent 14 years

(Cl. D64—11)

FIG. 1

Des. 194,856

PAGE 2

FIG. 2

Des. 194,856

PAGE 3

FIG. 3

FIG. 4

FIG. 1 is a front perspective view of an intelligence transmitter and receiver showing my new design.

FIG. 2 is a plan view thereof showing the rotating type member and keyboard arrangement.

FIG. 3 is an elevational view of the side opposite to that seen in FIG. 1 and

FIG. 4 is a rear elevational view thereof.

I claim:

The ornamental design for an intelligence transmitter and receiver, substantially as shown.
